BULK LADING CAR

Jack E. Gutridge, Dyer, Ind., assignor to Pullman
Incorporated, a corporation of Delaware

Filed Aug. 29, 1961, Ser. No. 66,538

Term of patent 14 years

(Cl. D66—1)

The figure is a perspective view of a bulk lading car, showing my new design.

The side and end of the car not shown in the drawing are substantially the same as those shown.

The essential features of my design reside in the portions shown in full lines.

I claim:

The ornamental design for a bulk lading car, substantially as shown and described.
